US0D1079419S

(12) **United States Design Patent** (10) **Patent No.:** **US D1,079,419 S**
(45) **Date of Patent:** **** Jun. 17, 2025**

(54) **WRENCH**

(71) Applicant: **Milwaukee Electric Tool Corporation**,
Brookfield, WI (US)

(72) Inventors: **Ian L. Christianson**, Wauwatosa, WI
(US); **Jared M. Amann**, New Berlin,
WI (US); **Devin W. Herritz**, Sussex,
WI (US)

(73) Assignee: **Milwaukee Electric Tool Corporation**,
Brookfield, WI (US)

(**) Term: **15 Years**

(21) Appl. No.: **29/875,314**

(22) Filed: **May 2, 2023**

Related U.S. Application Data

(62) Division of application No. 29/764,526, filed on Dec.
30, 2020, now Pat. No. Des. 1,002,309.

(57) **CLAIM**

The ornamental design for wrench as shown and described.

DESCRIPTION

FIG. 1 is a front perspective view from above of an embodiment of the claimed design;

FIG. 2 is a front perspective view from below of the claimed design of FIG. 1;

FIG. 3 is a rear perspective view from above of the claimed design of FIG. 1;

FIG. 4 is a front view of the claimed design of FIG. 1;

FIG. 5 is a rear view of the claimed design of FIG. 1;

FIG. 6 is a left side view of the claimed design of FIG. 1;

FIG. 7 is a right side view of the claimed design of FIG. 1;

FIG. 8 is a top view of the claimed design of FIG. 1;

FIG. 9 is a bottom view of the claimed design of FIG. 1;

FIG. 10 is a front perspective view from above of another embodiment of the claimed design;

FIG. 11 is a front perspective view from below of the claimed design of FIG. 10;

FIG. 12 is a rear perspective view from above of the claimed design of FIG. 10;

FIG. 13 is a front view of the claimed design of FIG. 10;

FIG. 14 is a rear view of the claimed design of FIG. 10;

FIG. 15 is a left side view of the claimed design of FIG. 10;

FIG. 16 is a right side view of the claimed design of FIG. 10;

FIG. 17 is a top view of the claimed design of FIG. 10; and,

FIG. 18 is a bottom view of the claimed design of FIG. 10.

The ornamental design which is claimed is shown in solid lines in the drawings. The broken dot-dash lines define boundaries of the claimed design and form no part thereof. The other broken lines in the drawings are for illustrative purposes only and form no part of the claimed design.

1 Claim, 12 Drawing Sheets
